DESIGN FOR A FEED SECTION UNIT FOR ELECTRICAL WIRING SYSTEMS

Joseph F. O'Brien, Lebanon, N. J.

Application July 17, 1945, Serial No. 120,763

Term of patent 14 years

(Cl. D26—5)

To all whom it may concern:

Be it known that I, Joseph F. O'Brien, a citizen of the United States of America, residing at Lebanon, in the county of Hunterdon and State of New Jersey, have invented a new, original, and ornamental Design for Feed Section Unit for Electrical Wiring Systems, of which the following is a specification, reference being had to the accompanying drawing, forming part thereof.

In the drawing:

Figure 1 is a top plan view of the feed section

unit for electrical wiring systems showing my new design;

Fig. 2 is a side elevation of the feed section unit shown in Fig. 1; and

Fig. 3 is a front end elevation of the feed section unit shown in Fig. 1.

I claim:

The ornamental design for a feed section unit for electrical wiring systems, as shown.

JOSEPH F. O'BRIEN.
